OR D 727

Design No. 727.

Edward Gleason's Design for Caster.

Patented September 11, 1855

Edward Gleason, of Dorchester, Mass.
Letter Patent No. 727. Dated Sept 11th 1855.

~~~~~  
The schedule referred to in these Letters Patent, and making part of the same.

~~~~~  
To all whom it may concern:

Be it known that I, Edward Gleason, of Dorchester in the
County of Norfolk, and State of Massachusetts, have invented or produced a new and orig-
inal design for a revolving door Table Carter, and I do herby declare that the following is a

full, and exact description of the same, reference being had to the annexed drawings making a part of this specification, in which,

Fig. 1. is an elevation of a caster showing my design.

Fig. 2. is a plan or top view of do.

Fig. 3. is a horizontal section of one of the doors of do.

Similar letters of reference indicate corresponding parts in the several figs.

A refers to the caster. B, are the doors. C, the feet, and D, the handle at the upper part of the caster.

The doors B, are of rectangular form, and such that their upper surface (a) upon it, the upper ends of which are pointed. On each convexity (a) there is formed leaves, (b) flowers, (c) and stems (d) the whole forming a plant, similar to a winter holly. The concave surfaces (a) are each encompassed by a narrow projecting strip (e) which is bevelled as shown in fig. 1. and the upper ends of the projecting strip (e) are curved and pointed as sharply shown in the above figure.

The feet C, have scrolls (f) and leaves upon them as shown in fig. 2.

The upper end of the caster has a circular projection (h), upon it, on which a wreath formed of roses and buds (i) and leaves (j) are formed as clearly shown in fig. 2.

The handle D, is formed of scrolls (k) and leaves (l), which are of curved form, and meet at the center or between the two scrolls see fig. 1.

I claim the wreath on the circular projection (h) and the embellishments on the doors, B, and feet C, when the whole are arranged and formed as herein shown to constitute an ornamental design for a Table Caster.
